(57) **CLAIM**

The ornamental design for a linear module hinged luminaire, as shown and described.

DESCRIPTION

FIG. 1 is a perspective view of the ornamental design of a linear module hinged luminaire.

FIG. 2 is a bottom view of the ornamental design of a linear module hinged luminaire.

FIG. 3 is a top view of the ornamental design of a linear module hinged luminaire.

FIG. 4 is a left view of the ornamental design of a linear module hinged luminaire.

FIG. 5 is a right view of the ornamental design of a linear module hinged luminaire.

FIG. 6 is a front view of the ornamental design of a linear module hinged luminaire.

FIG. 7 is a back view of the ornamental design of a linear module hinged luminaire.

FIG. 8 is a perspective view of the ornamental design of a linear module hinged luminaire in an open configuration.

FIG. 9 is a bottom view of the ornamental design of a linear module hinged luminaire in an open configuration.

FIG. 10 is a top view of the ornamental design of a linear module hinged luminaire in an open configuration.

FIG. 11 is a left view of the ornamental design of a linear module hinged luminaire in an open configuration.

FIG. 12 is a front view of the ornamental design of a linear module hinged luminaire in an open configuration.

FIG. 13 is a right view of the ornamental design of a linear module hinged luminaire in an open configuration; and,
FIG. 14 is a back view of the ornamental design of a linear module hinged luminaire in an open configuration.

The broken-line disclosure in the views is understood to represent portions of the article in which the claimed design is embodied, but which form no part of the claimed design.

1 Claim, 6 Drawing Sheets
